REMOTE CONTROL APPARATUS

Original Filed Jan. 31, 1929 2 Sheets-Sheet 2

UNITED STATES PATENT OFFICE

JOHN M. PELIKAN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

REMOTE-CONTROL APPARATUS

Application filed January 31, 1929, Serial No. 336,427. Renewed September 26, 1930.

My invention relates to remote control apparatus, and particularly to apparatus for safety controlling traffic governing devices, such as railway switches, from a distant 5 point.

One feature of my invention is the provision of means for controlling by current of a given character supplied to one pair of conductors, a switch and associated signals, a 10 switch indication, and three track circuit indications.

I will describe one form of apparatus embodying my invention, and will then point out the novel features thereof in claims.

15 The accompanying drawings, Figs. 1 and 2, when placed side by side, with Fig. 1 on the left, constitute a diagrammatic view showing one form of apparatus embodying my invention.

20 Referring to the drawings, the reference character $\bar{X}$ designates a stretch of main railway track connected with a siding Y by a switch F . The rails 1 and $1a$ of stretch X are divided by insulated rail joints 2 into track

25 sections A—B, B—C, and C—D. Each of the sections A—B, B—C and C—D is provided with a track circuit which is supplied with current by a battery 3 connected across the rails adjacent one end of the section, and

30 with a track relay G3, G2 or G1, respectively, connected across the rails adjacent the opposite end of the section. Sections A—B and C—D are known as approach sections, and their circuits are known as approach track 35 circuits. Section B—C is known as a detector section, and its circuit is known as a detector track circuit.

Slow releasing track circuit repeater relays $g1$ and $g3$ are controlled by front contacts of track relays G1 and G3 respectively. An approach indication relay T is controlled by one circuit passing through a back contact of relay G1 in series with a front contact of relay $g1$, and by a second circuit passing 45 through a back contact of relay G3 in series with a front contact of relay $g3$.

Signals S1, S2, S3 and S4 govern the movement of traffic over switch F which in its normal position directs traffic moves over 50 stretch X only, and which in its reverse posi-

tion directs moves over stretch X to or from siding Y . Signals S1, S2, S3, and S4 may be controlled in any suitable manner by relay H and by contacts operated by switch F , but such controls, forming no part of my 55 invention, are omitted from the drawings.

Switch F , as here shown, is operated by a motor M comprising an armature 5 and a field winding 6, which is controlled in the normal direction by a slow releasing relay $h1$ and in the reverse direction by a slow releasing relay $h2$. Relay $h1$ is in turn controlled by a front neutral and a normal polar contact of a slow releasing polarized relay H , and relay $h2$ is controlled by a front neutral and a reverse polar contact of relay H . A circuit controller designated by the reference character a is operated in conjunction with switch F . Circuit controller a is provided with a contact 131 which connects with a segment 131a at all times except while switch F is in its reverse position, and which connects with a segment 131b at all times except while switch F is in its normal position. Circuit controller a is also provided with a contact 32 which, while switch F is in its normal position, is in contact with a terminal 32a, and while switch F is in its reverse position, is in contact with a terminal 32b. 70

A polarized switch indication relay K is controlled in the normal direction by switch F in its normal position, and in the reverse direction by switch F in its reverse position. A slow pick-up relay P is controlled by a front neutral contact of relay K . A second switch indication relay I is controlled by a front contact of relay K in series with a back contact of relay P . 80

Switch control relay H is controlled over 90 a pair of conductors 55 and 64 by a lever V which may be included in a group with other similar levers in a control station such as a train dispatcher's office. Lever V has a normal position N , and a reverse position to the left designated by the reference character L , and a reverse position to the right designated by the reference character R . To energize relay H in the normal direction, lever V is operated to its L position, and to energize relay H in the reverse direction, lever 95 V is operated to its R position. 100

V is operated to its R position. Lever V is provided with seven contacts, 119, 52, 117, 49, 150, 172 and 83. Contacts 117, 119 and 150 are closed while lever V is in its R position only, contacts 49, 52 and 172 are closed while lever V is in its L position only, and contact 83 is closed while lever V is in its N position only.

Associated with lever V in the control station, are an approach indication relay E1, a detector circuit and switch indication relay E2, and a switch indication relay E3. Relay E3 is of a polarized type which when de-energized retains its contacts in the closed position corresponding with that controlled by the last previous direction of energization of the relay. Contact 153 of relay E3 connects with terminal 153a when relay E3 is energized by current flowing through contact 172 of lever V, and since, with switch F in its normal position, lever V has been operated to its L position next preceding its operation to its N position, contact 153 continues connected with terminal 153a while lever V is in its N position. Approach and detector circuit indication apparatus and switch indication apparatus are designated by the reference character e with distinguishing suffixes, and as here shown are electric lamps. The approach indication lamps eg1 and eg3 are controlled by relay E1, detector circuit indication lamp eg2 is controlled by relay E2, and switch indication lamps ef1 and ef2 are controlled by relay E3.

Current is supplied to conductors 55 and 64 and to the indication lamps by batteries Q1 and Q2 which are located adjacent lever V. Conductors 55 and 64 are also at times supplied with current by batteries Q3 and Q4 which are located adjacent switch F, and which also supply current for the operation of switch F. Resistance units 4 and 7 are employed to prevent the possibility of short circuits being caused by the de-energization of relays G1 and G3 at approximately the same time.

Having thus described, in general, the arrangement and location of the various constituent parts comprising my invention, I will now proceed to explain the operation of the apparatus.

As shown in the drawings, all parts are in their normal condition, that is, lever V is in its N position, track sections A—B, B—C and C—D are unoccupied, switch F is in its normal position for moves over stretch X only, and signals S1, S2, S3 and S4 are indicating "stop". Contact 153 of relay E3 being connected with terminal 153a, normal switch indication lamp ef2 is lighted by a circuit passing from battery Q2, through wires 42, 43 and 44, contact 153—153a, wire 45, filament of lamp ef2, and wires 46, 47 and 48 back to battery Q2. With relay G1 energized, relay g1 is energized by its circuit

passing from terminal 13 of battery Q4, through wires 14, 15 and 16, contact 17 of relay G1, wire 18, winding of relay g1, and wires 19, 20, 21, 22, and 23 to terminal 11 which is common to batteries Q3 and Q4. With relay G3 energized, relay g3 is energized by a similar circuit passing from terminal 13 of battery Q4, through wires 14, 15 and 24, contact 25 of relay G3, wire 26, winding of relay g3, wires 27, 20, 21, 22 and 23 to terminal 11. Since switch F is in its normal position, relay K is energized in the normal direction by a circuit passing from terminal 11, through wires 23, 22 and 28, winding of relay K, wire 29, contact 30 of relay T, wire 31, contact 32—32a of circuit controller a, and wire 33 to battery Q3. With relay K energized, relay P is also energized by a circuit passing from terminal 11, through wires 23 and 34, winding of relay P, wire 35, contact 36 of relay K, and wires 37 and 38 to battery Q3.

I will assume that, with all parts thus in their normal condition, a train approaching switch F from the west, that is, from the left, as shown in the drawings, deenergizes relay G3. Relay T is then energized in the reverse direction by a circuit passing from terminal 11, through wires 23, 22, 21 and 174, winding of relay T, wires 175 and 176, resistance unit 7, contact 156 of relay g3 wire 157, contact 158 of relay G3, and wires 159, 37 and 38 to battery Q3. Even though the opening of track relay G3 opens at contact 26 the circuit for relay g3, the latter relay does not release for a short interval of time because it is slow releasing in character. Relay T, being thus energized, completes, through its contact 60a, a circuit through the winding of approach indication relay E1 in the control station, this circuit passing from terminal 11, through wires 23, 22, 28 and 39, contact 88b of relay I, wires 87 and 86, contact 85 of relay H, wires 84 and 64, contact 83 of lever V, wires 82 and 54, winding of relay E1, wire 55, contact 56 of relay G2, wire 57, contact 58b of relay I, wire 59, contact 60a of relay T, wires 81 and 114, contact 80 of relay H, wire 79, resistance unit 4, wire 96, contact 97 of relay g3, wire 98, contact 99 of relay G3, and wire 100 to terminal 10 of battery Q3. Relay E1 is now energized in its normal direction, and hence lamp eg3 is lighted by a circuit passing from battery Q2, through wires 42, 43, 44 and 89, contacts 90 and 91a of relay E1, wire 101, filament of lamp eg3, and wires 102, 46, 47 and 48 back to battery Q2. After the lapse of sufficient time following the opening of the circuit of relay g3 by contact 25 of relay G3, relay g3 opens its contacts 97 and 156, thereby de-energizing relays E1 and T, respectively. Relay E1 then opens its contact 90, breaking the circuit and extinguishing the light of lamp eg3.

I will assume that with all parts again in their normal condition, as previously described, a westbound train approaching switch F de-energizes relay G1. Relay G1, by closing its back contact 103, causes the energization of relay T in the normal direction by a circuit passing from terminal 13 of battery Q4, through wires 14, 15 and 16, contact 103 of relay G1, wire 104, contact 105 of relay g1, resistance unit 7, wire 175, winding of relay T, and wires 174, 21, 22 and 23 to terminal 11. Relay T, through its contact 60a, now completes a circuit in the reverse direction through the winding of relay E1, this circuit passing from terminal 12 of battery Q4, through wire 74, contact 75 of relay G1, wire 76, contact 77 of relay g1, resistance unit 4, wires 78 and 79, contact 80 of relay H, wires 114 and 81, contact 60a of relay T, wire 59, contact 58b of relay I, wire 57, contact 56 of relay G2, wire 55, winding of relay E1, wires 54 and 82, contact 83 of lever V, wires 64 and 84, contact 85 of relay H, wires 86 and 87, contact 88b of relay I, and wires 39, 28, 22 and 23 to terminal 11. Relay E1, being energized in its reverse direction, causes lamp eg1 to be lighted by a circuit passing from battery Q2, through wires 42, 43, 44 and 89, contacts 90 and 91b of relay E1, wire 92, filament of lamp eg1, and wires 93, 94, 95, 47 and 48 back to battery Q2. After the lapse of sufficient time for relay g1 to open its front contacts following the de-energization of relay G1, relay T again becomes de-energized, by the opening of contact 105 of relay g1, causing relay E1 to become de-energized and extinguish the light of lamp eg1.

I will now assume that, with all parts again in their normal condition, the dispatcher desires to permit a train to move over switch F in its normal position. He therefore operates lever V to its L position, completing a circuit in the normal direction through relay H, this circuit passing from battery Q2, through wire 42, contact 49 of lever V, wire 50, winding of relay E2, wire 51, contact 52 of lever V, wires 53 and 54, winding of relay E1, wire 55, contact 56 of relay G2, wire 57, contact 58b of relay I, wire 59, contact 60b of relay T, wire 61, winding of relay H, and wires 62, 64 and 65 back to battery Q2. Relay H, now being energized in its normal direction, causes relay h1 to be energized by its circuit passing from terminal 13 of battery Q4, through wires 66 and 67, contacts 68 and 69a, of relay H, wire 70, contact 71 of relay h2, wire 72, winding of relay h1, and wires 73 and 23 to terminal 11. Relay E2, as well as relay H is operated by the circuit traced through the winding of relay H, closing the circuit of detector indicator lamp eg2 passing from battery Q2, through wires 42 and 43, contact 143 of relay E2, wire 144, filament of lamp eg2, and wires

94, 95, 47 and 48 back to battery Q2. While relays H and E2 are operated by the circuit through the windings of these relays, the current flowing in this circuit is not of sufficient magnitude to operate relay E1. When the front and normal contacts of relay H are closed while switch F is in its normal position, the arms of signals S2 and S3 are operated to the "proceed" position. 70

When an eastbound train approaches switch F while lever V is in its L position, de-energizing relay G3, the reverse control circuit for relay T becomes closed by contact 158 of relay G3 as previously described. Relay T being energized in its reverse direction, 75 the circuit for relay H is opened at contact 60b of relay T, and an approach indication control circuit is closed, passing from battery Q2, through wire 42, contact 49 of lever V, wire 50, winding of relay E2, wire 51, contact 52 of lever V, wires 53 and 54, winding of relay E1, wire 55, contact 56 of relay G2, wire 57, contact 58b of relay I, wire 59, contact 60a of relay T, wire 81, contact 113 of relay T, wire 112, contact 111 of relay H, 80 wire 110, contact 109b of relay T, wire 115, contact 116a of relay H, and wires 64 and 65 back to battery Q2. The current flowing in this circuit is of sufficient magnitude to operate relay E1 as well as relay E2, and hence 85 lamp eg3 becomes lighted by its circuit as previously traced. After the lapse of sufficient time following the de-energization of relay G3, relay g3 opens its contact 156, causing relay T to in turn become de-energized. 90 Relay E1, at its contact 90, then opens the circuit of lamp eg3. Relay H, being of a slow releasing type, does not open its front contacts during the open period of contact 60b of relay T, when relay T is energized as just described. 95

If, with all track sections again clear and with lever V in its L position, an approaching westbound train deenergizes relay G1, relay T becomes energized in its normal direction by its circuit passing through contact 103 of relay G1 as previously described. With relay T energized in its normal direction, the circuit for relay H is again open at contact 60b of relay T, and a second approach indication circuit is closed, passing from terminal 13 of battery Q4, through wires 14, 15 and 16, contact 103 of relay G1, wire 104, contact 105 of relay g1, wire 106, contact 107a of relay H, wire 108, contact 109a of relay T, wire 110, contact 111 of relay H, wire 112, contact 113 of relay T, wire 81, contact 60a of relay T, wire 59, contact 58b of relay I, wire 57, contact 56 of relay G2, wire 55, winding of relay E1, wires 54 and 53, contact 52 of lever V, wire 51, winding of relay E2, wire 50, contact 49 of lever V, wire 42, battery Q2, wires 65, 64 and 63, contacts 165a and 166a of relay T, wire 167, contact 168 of relay h1, and wire 38 to battery Q3. It will 120 125 130

be noted that, in the circuit just traced, batteries Q3 and Q4 in series oppose battery Q2. The combined potentials of batteries Q3 and Q4 are sufficiently in excess of the potential of battery Q2 to send current through this circuit in opposition to battery Q2 and of sufficient magnitude to operate relay E1 in the reverse direction. Lamp *eg1* then becomes lighted for a brief period by its circuit as previously described.

As a train approaching switch F proceeds into section B-C, de-energizing relay G2, the main circuit which operates relays E2 and H is opened at contact 56 of relay G2. Relay E2, upon becoming de-energized, opens the circuit of lamp *eg2*, extinguishing the light of this lamp and thereby showing to the dispatcher that the detector section is occupied. The de-energization of relay H causes the arms of signals S2 and S3 to be returned to the "stop" position.

I will assume that, when all track sections are again unoccupied, the dispatcher desires to send a train from stretch X over switch F to siding Y or in the reverse direction from siding Y over switch F to stretch X. He therefore operates lever V to its R position, causing current to be supplied to relay H in the reverse direction by a circuit passing from battery Q1, through wires 48, 65, 64 and 62, winding of relay H, wire 61, contact 60b of relay T, wire 59, contact 58b of relay I, wire 57, contact 56 of relay G2, wire 55, winding of relay E1, wires 54 and 53, contact 117 of lever V, wire 50, winding of relay E2, wire 118, contact 119 of lever V, and wire 120 back to battery Q1. The current flowing in this circuit passes through relay E2 in the same direction as the current in the circuit which is closed while lever V is in its L position, but in the reverse direction through relays E1 and H. Relay E2 is thus again energized in its normal direction, causing lamp *eg2* to become lighted, and retaining its contact 147 in the open position. The current flowing in the circuit is of insufficient magnitude to operate relay E1. Relay H, now being energized in its reverse direction, completes a circuit for relay *h2* passing from terminal 13 of battery Q4, through wires 66 and 67, contacts 68 and 69b of relay H, wire 121, contact 122 of relay *h1*, wire 123, winding of relay *h2*, and wires 124, 73 and 23 to terminal 11. With relay *h2* energized, the reverse operating circuit for motor M becomes closed, passing from terminal 13 of battery Q4, through wires 66 and 125, contact 126 of relay *h2*, wire 127, armature 5 of motor M, wire 128, contact 129 of relay *h2*, wire 130, contact 131a-131 of circuit controller a, wire 132, field winding 6 of motor M, and wire 133 to battery Q3. Motor M now operates switch F to its reverse position, and opens contact 131-131a thereby de-energizing motor M.

During the operation of switch F from its normal to its reverse position, the circuit for relay K through contact 32-32a of circuit controller a is opened when the switch leaves its normal position, and the reverse control circuit for relay K becomes closed through contact 32b-32 of circuit controller a upon the completion of the stroke of switch F. The reverse control circuit thus closed for relay K passes from terminal 13 of battery Q4, through wire 134, contact 32b-32 of circuit controller a, wire 31, contact 30 of relay T, wire 29, winding of relay K, and wires 28, 22 and 23 to terminal 11. Relay K is thus energized in its reverse direction.

During the de-energization of relay K, relay P, being de-energized by the opening of contact 36 of relay K, has closed its back contact 41. Upon the re-energization of relay K, a circuit becomes closed for relay I, passing from battery terminal 11, through wires 28, 22, 28 and 39, winding of relay I, wire 40, contact 41 of relay P, wire 35, contact 36 of relay K, and wires 37 and 38 to battery Q3. Relay P, having a slow pick-up, does not open its contact 41 until a short interval of time has elapsed after relay I has been energized. In the meantime, with the front contacts of relay I closed, a switch indication circuit has been completed, passing from terminal 13 of battery Q4, through wires 14 and 135, contacts 136b and 137 of relay K, wire 138, contact 88a of relay I, wires 87 and 169, contact 165b of relay T, wires 63, 64, 65 and 48, battery Q1, wire 120, contact 119 of lever V, wire 118, winding of relay E2, wire 50, contact 117 of lever V, wires 53 and 54, winding of relay E1, wire 55, contact 56 of relay G2, wire 57, contact 58a of relay I, wire 139, contacts 140 and 141b of relay K, and wire 142 to terminal 9 of battery Q3.

In the circuit just traced, the battery potential between terminals 9 and 13 sends current in opposition to battery Q1 and of sufficient magnitude to operate relay E2 in the reverse direction but not to operate relay E1. With relay E2 operated in the reverse direction, the reverse operating circuit for relay E3 becomes closed, passing from battery Q2, through wires 42, 43, 44 and 89, contact 145 of relay E1, wire 146, contacts 147 and 148 of relay E2, wire 149, contact 150 of lever V, wire 151, the right-hand terminal of the winding of relay E3, through the right-hand portion of the winding of relay E3, and wires 152, 95, 47 and 48 back to battery Q2.

Relay E3 then closes contact 153-153b, causing lamp *ef1* to be lighted by a circuit passing from battery Q2, through wires 42, 43 and 44, contact 153-153b of relay E3, wire 154, filament of lamp *ef1*, and wires 95, 47 and 48 back to battery Q2. After the lapse of a brief period of time, relay P opens its contact 41, thus de-energizing relay I

which then, by its contact 58b, again completes the reverse circuit for relay H, causing relay E2 to again become energized in its normal direction and open its contact 5 147, de-energizing relay E3 which, however, as already stated, does not open its contacts when it is de-energized. Lamp *ef1* therefore continues lighted.

When switch F has been operated to its reverse position and while the front and reverse contacts of relay H are closed, the arms of signals S1 and S4 are operated to their "proceed" position.

If now an approaching westbound train 15 de-energizes relay G1, another approach indication circuit is completed by relay T which becomes energized in its normal direction as previously described. The approach indication circuit which is now closed passes 20 from battery Q1, through wires 48, 65, and 64, contact 107b of relay H, wire 108, contact 109a of relay T, wire 110, contact 111 of relay H, wire 112, contact 113 of relay T, wire 81, contact 60a of relay T, wire 59, contact 25 58b of relay I, wire 57, contact 56 of relay G2, wire 55, winding of relay E1, wires 54 and 53, contact 117 of lever V, wire 50, winding of relay E2, wire 118, contact 119 of lever V, and wire 120 back to battery Q1. 30 With relay H now removed from the circuit, battery Q1 supplies sufficient current to operate relay E1 in its reverse direction as well as relay E2 in its normal direction. Lamp *eg1* therefore becomes lighted for a brief period as previously described.

When all the track sections are again unoccupied while lever V is in its R position, an eastbound train de-energizing relay G3 causes relay T to become energized in the reverse 40 direction and to complete still another approach indication circuit. This approach indication circuit passes from terminal 13 of battery Q4, through wires 66 and 125, contact 170 of relay h2, wire 171, contacts 166b 45 and 165a of relay T, wires 63, 64, 65 and 48, battery Q1, wire 120, contact 119 of lever V, wire 118, winding of relay E2, wire 50, contact 117 of lever V, wires 53 and 54, winding of relay E1, wire 55, contact 56 of relay G2, 50 wire 57, contact 58b of relay I, wire 59, contact 60a of relay T, wire 81, contact 113 of relay T, wire 112, contact 111 of relay H, wire 110, contact 109b of relay T, wire 115, contact 116b of relay H, wire 155, contact 156 of 55 relay g3, wire 157, contact 158 of relay G3, and wires 159, 37 and 38 to battery Q3. Batteries Q3 and Q4 now supply sufficient current through this circuit in opposition to battery Q1 to operate relay E1 in the normal direction as well as relay E2 in the reverse direction. Lamp *eg3* thereupon becomes lighted for a brief period as previously described.

If, when all the track sections are again unoccupied, the dispatcher desires to return 60 switch F to its normal position, he returns

lever V to its L position thus again closing the normal control circuit for relay H and causing the arms of signals S1 and S4 to be returned to the "stop" position. Relay H, upon being energized in its normal direction, 70 causes relay h1 to become energized by its circuit previously traced. Relay h1, upon becoming energized, completes the normal operating circuit for motor M, passing from terminal 13 of battery Q4, through contact 160 of relay h1, wire 161, armature 5 of motor M, wire 162, contact 163 of relay h1, wire 164, contact 131b—131 of circuit controller a, wire 182, field winding 6 of motor M, and wire 183 to battery Q3. Motor M then 75 returns switch F to its normal position. Upon completion of this operation of switch F, contact 131b—131 is opened, breaking the motor circuit.

During the operation of switch F from its reverse to its normal position, the reverse control circuit for relay K is opened at contact 32b—32 of circuit controller a when the switch leaves its reverse position, and the normal control circuit previously traced for 80 relay K becomes closed through contact 32—32a of circuit controller a upon the completion of the operation of switch F. Upon the re-energization of relay K in its normal direction, relay I becomes energized by its 85 circuit as previously traced. Upon the energization of relay I when switch F is returned to its normal position, a switch indication circuit becomes closed, passing from terminal 13 of battery Q4, through wires 14 and 135, contacts 141a and 140 of relay K, wire 139, contact 58a of relay I, wire 57, contact 56 of relay G2, wire 55, winding of relay E1, wires 54 and 53, contact 52 of lever V, wire 51, winding of relay E2, wire 50, contact 49 of 90 lever V, wire 42, battery Q2, wires 65, 64 and 63, contact 165b of relay T, wires 169 and 87, contact 88a of relay I, wire 138, contacts 137 and 136a of relay K, and wire 142 to terminal 9 of battery Q3. By means of this circuit, the potential between battery terminals 9 and 13 sends current in opposition to battery Q2 and of sufficient magnitude to operate relay E2 in its reverse direction, but not of sufficient magnitude to operate relay E1. 95 Relay E2 thereupon closes its contact 147, completing a circuit through the left-hand portion of the winding of relay E3, this circuit passing from battery Q2, through wires 42, 43, 44 and 89, contact 145 of relay E1, 100 wire 146, contacts 147 and 148 of relay E2, wire 149, contact 172 of lever V, wire 173, left-hand terminal of the winding of relay E3, the left-hand portion of the winding of relay E3, and wires 152, 95, 47 and 48 back 105 to battery Q2. The normal switch indication lamp *ef2* then becomes lighted by its circuit through contact 153—153a of relay E3 as previously described.

Although I have herein shown and de- 110

scribed only one form of remote control apparatus embodying my invention, it is understood that various changes and modifications may be made therein within the scope of the appended claims without departing from the spirit and scope of my invention.

Having thus described my invention, what I claim is:

1. In combination, a railway traffic governing device, a first and a second and a third section of railway track, a track circuit for each of said sections each including a track relay, a pair of conductors, means for supplying current of a given character to said conductors at a first voltage for controlling said traffic governing device, an indication means, means controlled by said traffic governing device for supplying current of said given character to said conductors at a second voltage for controlling said indication means, a second and a third and a fourth indication means, and means controlled by said first and second and third track relays for supplying current of said given character to said conductors for controlling said second and third and fourth indication means respectively.
2. In combination, a railway traffic governing device, a first and a second and a third section of railway track, a track circuit for each of said sections each including a track relay, a pair of conductors, means for supplying current of a given character and of normal polarity to said conductors for controlling said traffic governing device, an indication means, means controlled by said traffic governing device for supplying current of said given character but of reverse polarity to said conductors for controlling said indication means, a second and a third indication means, means controlled by said first and second track relays for supplying said conductors with current of said given character but of greater magnitude than the current which controls said traffic governing device and said first indication means, means including said current of greater magnitude for controlling said second or said third indication means according as said current is of normal or reverse polarity respectively, a fourth indication means, and means controlled by said third track relay for supplying current of said given character to said conductors for controlling said fourth indication means.
3. In combination, a railway switch, a polarized switch indication relay energized in its normal or its reverse direction according as said switch is in its normal or its reverse position respectively, a second indication relay controlled by a neutral front contact of said polarized indication relay, a third indication relay controlled by a back contact of said second indication relay and by a neutral front contact of said polarized indication relay, a first and a second conductor, a second polarized indication relay, a manually operable lever having a normal position and a first and a second reverse position, a circuit including the winding of said control relay and a neutral back contact of said first polarized indication relay as well as said first and second conductors and the winding of said second indication relay in series, means for

supplying said circuit with current of normal or reverse polarity according as said lever is operated to its first or its second reverse position, respectively, said current being of sufficient magnitude to operate said switch control relay but not said second indication relay, an indication circuit including a front contact of said first indication relay and a back contact of said control relay as well as 5 a front contact of said first repeater relay and a back contact of said first track relay and also said first and second conductors and the winding of said second indication relay in series and a contact closed while said lever is 10 in its normal position, means for supplying said indication circuit with current of normal polarity to operate said second indication relay in its normal direction, a branch path around said contacts of said first track 15 relay and said first repeater relay in said circuit including a front contact of said second repeater relay and a back contact of said second track relay, means for supplying said indication circuit through said branch path 20 with current of reverse polarity to operate said second indication relay in its reverse direction, means for controlling the operation of said switch by said switch control relay, and indication means controlled by said second indication relay.

5. In combination with a railway switch, a first and a second section of railway track, a track circuit for each of said sections each including a track relay, a first slow releasing 35 repeater relay controlled by a front contact of said first track relay, a second slow releasing repeater relay controlled by a front contact of said second track relay, a first polarized indication relay controlled by current 40 of normal polarity flowing in a circuit including a back contact of said first track relay and a front contact of said first repeater relay and by current of reverse polarity flowing in a circuit including a back contact of 45 said second track relay and a front contact of said second repeater relay, a polarized switch control relay, a first and a second conductor, a second polarized indication relay, a manually operable lever having a first and 50 a second position, a circuit including the winding of said control relay and a neutral back contact of said first polarized indication relay as well as said first and second conductors and the winding of said second indication 55 relay in series, means for supplying said circuit with current of normal or reverse polarity according as said lever is in its first or its second position respectively, said current being of sufficient magnitude to operate 60 said switch control relay but not said second indication relay, around said control relay winding and said first indication relay back contact in said circuit a branch path including a front and a normal contact of said first

indication relay and a front and a normal contact of said control relay as well as a front contact of said first repeater relay and a back contact of said first track relay, means for supplying said circuit through 70 said branch path with current of reverse polarity and of sufficient magnitude to operate said second indication relay in its reverse direction, in multiple with said first branch path, a second branch path including a front and a reverse contact of said first indication relay and a front and a normal contact of said control relay, means for supplying said circuit through said second branch path with current of normal polarity and of sufficient 75 magnitude to operate said second indication relay in its normal direction, in multiple with said first branch path, a third branch path including a front and a normal contact of said first indication relay and a front and a reverse contact of said control relay, means for supplying said circuit through said third branch path with current of reverse polarity and of sufficient 80 magnitude to operate said second indication relay in its reverse direction, in multiple with said first branch path, a fourth branch path including a front and a reverse contact of said first indication relay and a front and a reverse contact of said control relay and also a front contact of said second repeater relay and a back contact of said second track relay, means for supplying said circuit through said fourth branch path with current of normal polarity and of sufficient 85 magnitude to operate said second indication relay in its normal direction, means for controlling the operation of said switch by said control relay, and indication means controlled by said second indication relay.

In testimony whereof I affix my signature. 105
JOHN M. PELIKAN.
